(57) CLAIM

The ornamental design for a camera strap and connector clip for use with the same, as shown and described.

DESCRIPTION

FIG. 1 is a front view of the camera strap and connector clip for use with the same in accordance with the present design; FIG. 2 is a left side view thereof;

FIG. 3 is a right side view thereof; and,
FIG. 4 is a rear view thereof.
